UNITED STATES PATENT OFFICE.

PERCY R. DRENNING, OF BALTIMORE, MARYLAND, ASSIGNOR, BY MESNE ASSIGNMENTS, TO THE SYMINGTON COMPANY, A CORPORATION OF MARYLAND.

DRAFT RIGGING.

Application filed December 29, 1923. Serial No. 683,482.

To all whom it may concern:

Be it known that I, Percy R. DRENNING, a citizen of the United States, residing at Baltimore, in the State of Maryland, have invented certain new and useful Improvements in Draft Rigging; and I do hereby declare the following to be a full, clear, and exact description of the invention, such as will enable others skilled in the art to which it appertains to make and use the same.

The invention relates to railway draft rigging and more particularly to an improved draft gear attachment of the single key type.

An important object of the invention is to provide a railway draft rigging in which the yoke is slidably connected to the coupler, the latter being received into a relatively deep recessed portion of the front follower member, said member being of a relatively increased depth and of great strength value.

Another object of the invention is to provide a railway draft rigging involving a front follower block of very light weight but maximum strength value, said block being easily manufactured as a casting and capable of being applied to the draft rigging without reducing the pocket room therein receiving the cushioning mechanism.

A still further object of the invention is to provide a railway draft rigging in which the butt end of the coupler is received and guided by means of the front follower member, portions of said follower extending forwardly of the end of the coupler butt and contacting an upper front stop member bridging the center sills and forming the striking casting, said forwardly extending portions of the follower also contacting a lower front stop member bridging the center sills and providing the coupler carry iron.

The invention has for a further object the provision of a railway draft rigging including a horizontal yoke slidably connected to the coupler, upper and lower front stop members tying the center sills or draft sills, said stop members terminating short of the coupler butt, a relatively deep follower block interposed between the coupler and the cushioning mechanism, said follower block having forwardly extending portions contacting the respective upper and lower stop members, said forwardly extending portions in addition to embracing the

butt of the coupler also being of a length equal to the increased spacing of the rear stop member and front stop members, which spacing is in excess of the standard A. R. A. dimensions and can by the present construction be satisfactorily utilized without sacrificing the pocket room receiving the cushioning mechanism or otherwise interfering with the usual operation of a single key attachment.

The invention further consists in the combination, construction and arrangement of the several parts hereinafter described and pointed out in the claims.

In the drawings chosen to illustrate my invention and wherein similar reference characters designate corresponding parts in the several views:

Figure 1 is a top plan view of a railway draft rigging constructed in accordance with my invention and shown applied to the center sills or draft sills, portions of said figure being broken away and shown in section.

Figure 2 is a vertical longitudinal sectional view on the line 2—2 of Fig. 1, the coupler being shown in elevation.

Figure 3 is a horizontal sectional view through the forward end of the draft rigging showing the coupler and key connecting the same to the yoke in top plan view.

Figure 4 is a view in end elevation showing the draft rigging pocket formed between the center sills and upper and lower stop members providing respectively the striking casting and coupler carry iron.

Figure 5 is a vertical longitudinal sectional view on the line 5—5 of Fig. 4, viewed in the direction of the arrows.

In the drawings the center sills 1—1 are adapted to receive therebetween the horizontal yoke 2 slidably connected to the coupler 3 by means of a key 4. The forward ends of the center sills are connected by an upper tie casting 5 and a lower tie casting 6, said castings bridging the center sills and providing front stop members co-acting with the front follower 7.

The upper tie casting and stop member 5 is provided with a forwardly extending portion constituting the striking casting 8. A plurality of longitudinally extending vertically disposed webs 9 unite the striking casting with the stop portion 10, the outermost of said webs providing the side walls of the casting and being rigidly connected

to the center sills by means of rivets 11. The webs 9 extend upwardly from the transverse body web portion of the casting extending the full width of the center sills. 5 Both the stop portion 10 and striking casting 8 are further reinforced by transversely extending flanges or webs 12 uniting the longitudinally extending webs 9, as shown. The outermost webs or side walls of the 10 casting extend rearwardly of the stop portion and are firmly connected to the center sills by means of rivets 13.

The lower stop member and tie casting 6 is of channel cross section at its forward end and 15 provides the coupler carry iron 14 which, as shown, may receive a suitable filler or wear member 15 upon which the coupler bears. A transverse horizontal web 16 unites the channel portion of the casting 20 with the rear stop portion 17 thereof, a plurality of longitudinally extending and vertically disposed webs 18 projecting above and below said transverse web and uniting the striking portion with the stop portion of 25 the casting. A transversely and forwardly extending flange 19 is provided for reinforcing the stop portion of the casting, said flange uniting the several vertically disposed webs 18. The lower casting 6 is provided 30 with outwardly extending flanges 20 disposed longitudinally thereof and adapted to underlie the lower flanges of the center sills and be connected thereto by means of a plurality of rivets 21. The rear ends of 35 the flanges 20 extend beyond the stop portion of the casting and are connected to the center sills by means of the rivets 22.

The coupler butt extends beyond the stop faces of the upper and lower castings 5 and 40 6 bridging the center sills, said butt being received in the pocket or recess 23 provided in the follower block 7. The pocket 23 lies between the upper and lower walls 24, opposite side walls 25 and the vertical transverse wall 26, said pocket or recess being 45 of sufficient depth to prevent the butt of the coupler entirely leaving the pocket under service conditions. A wall or flange 27 surrounds the forward open end of the pocket 50 or recess 23, the upper and lower portions of said wall being adapted to contact the faces of the stop portions 10 and 17 of the respective castings 5 and 6. The follower block is provided with a rear wall 28, said 55 wall being spaced from the transverse web or wall 26 but connected thereto by means of a plurality of vertical and horizontally intersecting webs 29. Suitable core openings 30 are provided in the wall 28 to facilitate the casting of the intersecting horizontal and vertical webs designed to advantageously reinforce the block and permit 60 of a relatively light weight construction.

The surrounding flange 27 and the wall 65 28 are united by a plurality of vertically

disposed longitudinally extending ribs 31, said ribs acting to reinforce the block and projecting from the upper and lower walls 24 bordering the coupler butt pocket. The outer edge portions of the flange 27 are also 70 united with the wall 28 by means of horizontally disposed webs 32 extending from the oppositely disposed walls 25 bordering the pocket 23 in the follower member. It will be observed that the longitudinally extending reinforcing webs 31 and 32 extend 75 the full depth of the follower block, thereby adequately providing for the transmission of the loads between the cushioning mechanism and the front stop members. It will 80 also be noted that the relatively increased depth of the follower block permits of the coupler butt being maintained within the pocket 23 without reducing the pocket receiving the cushioning mechanism, indicated 85 in dot and dash lines in Figure 1, the front stop members, as a result of said construction, being disposed forwardly of the end of the coupler butt, as clearly shown. The follower is supported upon a cross member 33 90 connected to the respective center sills by suitable bolts or rivets. Additional cross members 34 and 35 are adapted to bridge the center sills above and below the cushioning mechanism for maintaining the same in 95 operative position, as will be understood. A rear filler block 36 is preferably interposed between the cushioning mechanism and the inner face of the yoke, said yoke 100 filler block extending above and below the yoke, as clearly shown in Figure 2. The rear stop member 37 is provided with a vertical transverse buffering web 38 disposed rearwardly of the upper and lower transverse projecting portions 39 and 40 disposed 105 adjacent the projecting portions of the filler block 36. The rear end of the yoke 2 is adapted to contact the buffering web 38 between the forwardly extending portions 39 and 40. The upper and lower transverse 110 flanges 39 and 40 are united with the opposite side walls of the casting by means of the obliquely disposed portions intersecting said side walls in substantially a vertical plane passing through the buffering web 38. 115 The upper transverse web is shown as reinforced by the bracing web 41 extending from the top wall 42 of the casting, said top wall uniting the opposite side walls 43 and 44. The bottom wall of the casting is indicated by the numeral 45, said bottom wall and top wall being united by the rearwardly extending vertically disposed web 46, said 120 last named web being intersected by a horizontal transverse web 47 uniting the side walls and buffering wall 38 of the casting. The rear end of the web 47 is flanged in the 125 nature of a beam, the depth of said beam being greater at the center than at the sides of the back stop, thereby permitting the 130

introduction of the stop member without interfering with the bolster center filler casting. A plurality of intermediate ribs 49 is also provided between the horizontal transverse web and the buffing wall 38. Suitable rivets 48 firmly connect the opposite side walls to the center sills 43 and 44 of the back stop casting to the center sill.

A railway draft rigging constructed in accordance with my present invention provides a very strong and durable construction in which the upper and lower front stop members and front follower block cooperate to permit of the coupler butt being effectively controlled without reducing the travel of the draft gear or otherwise causing a reduction in its capacity. It will be observed that the relatively increased distance between the front and rear stop members of the draft rigging over the standard A. R. A. dimensions is taken care of by the improved construction of follower block, the forwardly extending portions of said block encircling the coupler butt being equal in length to the increased spacing of the stop members.

I claim:

1. In a railway draft rigging, the combination with center sills, of a coupler, a yoke slidably connected to said coupler, a follower member contacting the rear end of the coupler and having forwardly extending portions embracing the butt thereof, a cushioning mechanism interposed between said follower and yoke, a rear stop member cooperating with the yoke, and front stop members cooperating with the forwardly extending portions of the follower member, said front stop members being spaced from the rear stop member a distance in excess of the A. R. A. dimensions for co-action with the standard length coupler, said follower member acting to guide said coupler and being interposed between the cushioning mechanism and front stop members so as to maintain the full depth of pocket receiving said cushioning mechanism.

2. In a railway draft rigging, the combination with center sills, of a standard coupler having a yoke slidably connected thereto, a cushioning mechanism, a follower block adapted to guide the butt of the coupler and interposed between said coupler and cushioning mechanism, and stop members cooperating respectively with said yoke and follower block, said follower block being of a relatively increased depth, which increase in depth is disposed forwardly of the end of the coupler for maintaining the full depth of pocket room receiving the cushioning mechanism.

3. In a railway draft rigging, the combination with center sills, of a coupler, a yoke slidably connected to said coupler, a rear stop member coacting with said yoke, a

cushioning mechanism, front stop members connected to the center sills, and a front follower interposed between said front stop members and the cushioning mechanism, said follower having a forwardly disposed flange contacting the front stop members and a rearwardly spaced wall portion interposed between the end of the coupler and cushioning mechanism, and surrounding wall portions uniting said flange and rear wall portion for forming a pocket adapted to receive the butt of the coupler.

4. In a railway draft rigging, the combination with center sills, a coupler, a yoke slidably connected to said coupler, a rear stop member co-acting with said yoke, a cushioning mechanism, front stop members connected to the center sills, and a front follower interposed between said front stop members and the cushioning mechanism, said follower having a forwardly disposed flange surrounding the coupler butt and a rear wall contacting the cushioning mechanism, and a plurality of longitudinally disposed webs uniting said flange and rear wall.

5. In a railway draft rigging, the combination with center sills, a coupler, a yoke slidably connected to said coupler, a rear stop member co-acting with said yoke, a cushioning mechanism, front stop members connected to the center sills, and a front follower interposed between said front stop members and the cushioning mechanism, said follower having a forwardly disposed flange surrounding the coupler butt and a rear wall contacting the cushioning mechanism, and longitudinally disposed surrounding wall portions uniting said flange and rear wall, said surrounding wall portions acting to embrace the butt of the coupler for guiding the same.

6. In a railway draft rigging, the combination with center sills, of a coupler, a yoke slidably connected to said coupler, a rear stop member co-acting with said yoke, a cushioning mechanism, front stop members connected to the center sills, and a front follower interposed between said stop members and the cushioning mechanism, said follower having a forwardly disposed wall adapted to contact the front stop members, a plurality of spaced rear walls one of which contacts the cushioning mechanism, and the other of which contacts the end of the coupler, and a plurality of longitudinally disposed webs uniting said forwardly disposed wall and spaced rear walls, said webs being adapted to embrace the butt of the coupler.

7. In a railway draft rigging, the combination with center sills, of a coupler, a yoke slidably connected to said coupler, a rear stop member co-acting with said yoke, a cushioning mechanism, front stop members connected to the center sills, and a front follower interposed between said stop mem-

- bers and the cushioning mechanism, said follower having a forwardly disposed wall adapted to contact the front stop members, a rear wall adapted to contact the cushioning mechanism, and a plurality of longitudinally extending webs uniting said walls, said webs being adapted to embrace and guide the butt of the coupler throughout its full travel.
10. 8. In a railway draft rigging, the combination with center sills, of a coupler, a yoke slidably connected to said coupler, a cushioning mechanism, a follower block adapted to contact said cushioning mechanism and having forwardly extending portions designed to embrace the butt of the coupler, and front stop members arranged above and below said coupler and connected to the center sills, said stop members bridging the center sills and having stop faces terminating short of the inner end of the coupler for co-action with said forwardly extending portions of the follower.
9. A follower block for railway draft rigging comprising a plurality of longitudinally disposed wall portions adapted to embrace a coupler butt and having an outwardly extending surrounding flange at one end thereof forming a front wall, a rear wall providing a closure for the opposite ends of said wall portions and adapted to contact the cushioning mechanism of the draft rigging, and means reinforcing said flange and rear wall.
10. A follower block for railway draft rigging comprising a plurality of longitudinally disposed wall portions adapted to embrace a coupler butt and having an outwardly extending surrounding flange at one end thereof forming a front wall, a plurality of rear walls forming a closure for the opposite ends of said wall portions and a contacting face for cooperation with the cushioning mechanism, a plurality of webs uniting said rear walls, and a plurality of webs uniting said surrounding flange and rear walls.

In testimony whereof I affix my signature.

PERCY R. DRENNING.
